E. J. SWEETLAND,
PACKING AND THE LIKE,
APPLICATION FILED JAN. 20, 1916.

1,225,286.

Patented May 8, 1917.

Ernest J. Sweetland INVENTOR.

BY

G. E. Terwilliger ATTORNEY

UNITED STATES PATENT OFFICE.

ERNEST J. SWEETLAND, OF MONTCLAIR, NEW JERSEY.

PACKING AND THE LIKE.

1,225,286.

Specification of Letters Patent.

Patented May 8, 1917.

Application filed January 20, 1916. Serial No. 73,130.

To all whom it may concern:

Be it known that I, ERNEST J. SWEETLAND, a citizen of the United States, residing in the town of Montclair, county of Essex, and 5 State of New Jersey, have invented certain new and useful Improvements in Packing and the like, of which the following is a specification.

My invention relates to a new article of manufacture, which is especially adapted for use as a packing in connection with steam or water pipes, steam engines, valves, air compressors and in many other situations which will occur to those skilled in such 10 matters. Such a substance should first of all be waterproof or be fluid tight, and consequently, it is desirable that rubber, from the nature of its qualities, shall enter into the material to a considerable degree being compressible, resilient and waterproof. At the 15 same time rubber when used alone is liable to an undesirable degree of distortion and has not sufficient body or resistance against tearing for many purposes. My invention therefore contemplates combining with the rubber a suitable fabric to add additional body and strength, without appreciably interfering with the valuable qualities which the rubber inherently possesses. I have 20 found that a fabric in which one or both of the sets of threads interwoven to form it are composed of bundles of metallic filaments or filamental metallic wires is peculiarly well suited for this purpose.

In the accompanying drawings which form a part of this specification, Figure 1 is a plan view of one type of fabric adapted for these purposes. Fig. 2 is a transverse sectional view of the structure of Fig. 1. 25 Fig. 3 is a diagrammatic plan view of the structure of Fig. 1 after it has been flattened under pressure, as by rolling. Fig. 4 is a view similar to Fig. 1, showing a modified form of construction in which the bundles 30 of filaments, forming one set of threads, are replaced by individual wires. Fig. 5 is a transverse sectional view of the structure of Fig. 4, showing two sheets or slabs of rubber about to be incorporated therewith. Fig. 6 35 is a view similar to Fig. 5, but showing the completed structure. Fig. 7 is a view similar to Fig. 2, showing diagrammatically the result of the structure formed by incorporating rubber with the metallic fabric in a different manner. Fig. 8 is a diagrammatic view similar to Fig. 1 but showing a twill

fabric. Fig. 9 is a transverse sectional view of the structure of Fig. 8. Fig. 10 is a view similar to Fig. 9, showing diagrammatically the appearance of the structure formed by 60 incorporating rubber with the fabric of Fig. 9. Fig. 11 is a diagrammatic representation of the fabric obtained by flattening the fabric of Figs. 8 and 9 under pressure, as by 65 rolling. Fig. 12 is a diagrammatic representation of the surface appearance of the structure of Fig. 11. Fig. 13 is a view similar to Fig. 10, showing the application of rubber to the fabric of Fig. 11.

Referring to the drawings in detail, and 70 particularly to Figs. 1 and 2, the numeral 1 designates a filter fabric composed of interwoven warp threads 2, and weft threads 3, each of which threads may be composed of a plurality or bundle of fine wires. Each 75 bundle of wires may be formed into a strand before weaving by giving a slight longitudinal twist to the strand, five or six turns to the foot being ample for most purposes, or the wires may be conveniently aggregated 80 while lying approximately parallel to each other, by the use of soap, wax or other adhesive, which will cause the plurality of wires composing a bundle to cling together 85 during the process of weaving, but which may be eliminated after the weaving of the fabric is completed by applying heat or a solvent, as the nature of the particular adhesive used may require. However, in many 90 instances, I have found the use of either adhesive or twisting to be unnecessary.

In using the word "bundle" in this specification and in the appended claims I intend it to be considered simply as a convenient term for describing a plurality of 95 wires forming a strand, and I do not desire to limit it to a structure in which the wires or filaments are secured to each other, either by twisting or any other way, such as the use of soap, wax or other adhesive. It will 100 be obvious that the number of filaments or wires forming a bundle may vary within wide limits as the nature of the specific use to which the fabric is to be applied may dictate, and in some instances the number 105 may be as small as 3 to 5 wires to each bundle or strand, while in other cases it will greatly exceed this. The dimension of the individual wires may also be varied within appropriate limits. For some purposes 110 wires 0.003 of an inch in diameter are found heavy enough, but for average use the size

may be increased to a considerable degree. Wires of this general nature may be called "filamental wires", and this term is consequently used for brevity and convenience in 5 this specification and in the appended claims.

The interweaving of sets of threads forming bundles or strands such as I have described produces a flexible, and to a degree, a compressible fabric, having hundreds of 10 interstices to the square inch, the exact number depending, of course, on the number of wires or filaments to the lineal inch.

Subjecting such a fabric to pressure to flatten it results in the formation of the 15 structure diagrammatically illustrated in Fig. 3. This flattening operation may be carried on in a variety of ways, but is preferably accomplished by rolling the woven fabric between pressure rolls, the distance 20 between which may be adjusted with great precision. For some purposes I find it desirable to form one set of threads of individual wires instead of bundles of wires, and this structure is illustrated in Figs. 4 25 and 5, in which the numeral 4 designates the warp wires, the weft threads 5 being bundles of filaments as before. Of course, if desired, the individual wires may be the weft threads.

30 Rubber may be incorporated with the fabric by forcing two sheets or slabs 6 and 7 of rubber in a plastic or semi-plastic condition into the fabric, and then vulcanizing the whole. This results in the production of 35 a unitary sheet 8 of rubber in which the fabric is embedded, as clearly shown in Fig. 6. There are a variety of ways in which the rubber may be incorporated with the fabric, as by applying rubber to opposite 40 surfaces of the fabric, while the former is in a very plastic condition, by dipping or by, in effect, filtering rubber solution or extremely plastic rubber through the fabric, thus producing, when the material of Figs. 45 1 and 2 is used, a structure 9 which is diagrammatically shown in Fig. 7 in which the rubber follows more closely the contour of the surface of the material, but at the same time is substantially homogeneous throughout 50 the cross-section of the substance.

While in Figs. 1 to 7 inclusive I have shown a fabric of the so-called "basket weave", it will be apparent that any other suitable form of weave may be utilized for 55 the purpose as, for instance, the twill diagrammatically shown in Figs. 8 and 9. Fig. 10 illustrates diagrammatically the effect of applying rubber to this form of fabric. Figs. 11 and 12 show diagrammatically the 60 effect of flattening such a fabric under pressure, as by rolling, before the application of the rubber, while Fig. 13 shows the resulting rubberized sheet. In some instances I find it desirable to apply the rubber to the 65 unrolled fabric, thus producing an effect like

Fig. 10, and then to pass the article thus formed through calendering rolls to obtain a material similar to that shown diagrammatically in Fig. 13.

It will be appreciated that the drawings are largely diagrammatic in character, and that in actual construction the parts may be so tightly woven that the interstices appearing in Figs. 8 and 9 may, to a great extent, disappear, even before the fabric is rolled. 75

Owing to the thread-like nature of the metallic filaments or wires of which the fabric is composed, hundreds of interstices exist in it per square inch, and this number may be increased or decreased within limits 80 by selecting the desired number of filaments per lineal inch. When the rubber permeates the fabric, it of course passes through its interstices and thereby forms a strong bond with the fabric. From its very nature the 85 woven fabric which I have described is pliant, flexible and to some extent compressible, and consequently there is little tendency for it to pull away from the rubber with which it is incorporated no matter 90 what the strain may be to which the combined material may be subjected. At the same time the filamental metallic fabric gives to the rubber a strength and resistance 95 against tearing which is highly desirable 100 for many purposes.

As I have above pointed out there is normally a close bond between the metal fabric and the rubber, but under special conditions it may be desirable to increase this 105 bond so that it amounts to an actual chemical union between the metallic filaments and the rubber. The combining of the rubber with each individual filament in this manner, thereby, in effect, making the filamental 110 fabric a part of the rubber and vice versa, and conferring upon each the useful attributes of the other, may be accomplished by bonding the filaments and rubber in the manner described in United States Letters 115 Patent to Daft, Nos. 1,036,576, 1,120,794 and 1,120,795.

While I have illustrated and described only certain specific embodiments of my invention I realize that it is susceptible of 115 wide application, and I do not desire to be limited to the precise construction shown and described.

Having thus described my invention, I claim:—

1. An article of manufacture comprising a woven metallic fabric embedded in rubber, said rubber being secured to the fabric by a chemical bond.

2. An article of manufacture comprising 125 a woven fabric, one set of threads of which is composed of bundles of metallic wires, said fabric being embedded in rubber.

3. An article of manufacture comprising 130 a woven fabric, one set of threads of which

- is composed of bundles of metallic wires, said fabric being flattened under pressure and embedded in rubber.
4. An article of manufacture comprising 5 a woven fabric, one set of threads of which is composed of bundles of metallic wires, said fabric being flattened under pressure and having rubber incorporated therewith throughout its mass.
- 10 5. An article of manufacture comprising a woven fabric, one set of threads of which is composed of bundles of metallic wires, said fabric being rolled under pressure after weaving to flatten the same and having rubber incorporated therewith throughout its mass.
- 15 6. An article of manufacture comprising a woven fabric, one set of threads of which is composed of bundles of metallic wires, 20 said fabric being elongated under pressure in one direction more than another, after weaving, as by rolling, and having rubber incorporated therewith throughout its mass.
- 25 7. An article of manufacture comprising a woven fabric, one set of threads of which is composed of twisted bundles of metallic wires, said fabric being elongated under pressure in one direction more than an-
- other, after weaving, as by rolling, and having rubber incorporated therewith 30 throughout its mass.
8. An article of manufacture comprising a woven fabric, both the warp and the weft of which include bundles of metallic wires, 35 said fabric being flattened under pressure, and having rubber incorporated therewith throughout its mass.
9. An article of manufacture comprising a woven fabric, the warp and the weft of which include twisted bundles of metallic 40 wires, said fabric being flattened under pressure and having rubber incorporated therewith throughout its mass.
10. An article of manufacture comprising a closely woven fabric presenting substantially no interstices, both the warp and the weft of which include bundles of metallic wires, said fabric having rubber incorporated therewith throughout its mass. 45
11. An article of manufacture comprising a closely woven fabric presenting substantially no interstices, both the warp and the weft of which include twisted bundles of metallic wires, said fabric having rubber incorporated therewith throughout its mass. 55

E. J. SWEETLAND.
